CLAIM

An ornamental design for a vehicle fender, as shown and described.

DESCRIPTION

FIG. 1 is a left side elevational view of a left vehicle fender (the right vehicle fender being a minor image and is not shown);

FIG. 2 is a front elevational view of the vehicle fender;

FIG. 3 is a rear elevational view of the vehicle fender;

FIG. 4 is a top plan view of the vehicle fender;

FIG. 5 is a bottom plan view of the vehicle fender; and,

FIG. 6 is a perspective view of the vehicle fender.
